CLAIM

The ornamental design for a Christmas light, as shown and described.

DESCRIPTION

FIG. 1 is a front elevational view of a Christmas light showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.

The broken lines in the figures are for the purposes of illustrating portions of the Christmas light, which form no part of the claimed design.

1 Claim, 8 Drawing Sheets---
